UNITED STATES PATENT OFFICE.

FRANK G. HANBACK, OF ALLEGANY, NEW YORK.

STATIC-INDUCTION TOY.

Application filed February 28, 1927. Serial No. 171,632.

The invention relates to toys of the type in which a play piece is movable between a board and a transparent plate, under the influence of static currents induced by friction upon the plate, and it is the principal aim of such invention to provide a toy in which a simulation of an animate object is embodied and in which the faculty of eating is amusingly represented.

- 10 In carrying out the above end, further objects are to provide one or more play pieces in the form of "food" (actual or representation) which may be moved toward the mouth of the animate simulation under the influence of the induced static currents; to embody at least one of the play pieces in such form as to represent a part, which the animate object simulated, commonly moves while eating; specifically, to embody at least said one play piece in the form of a movable mouth part and to make novel provision whereby such part guards a mouth opening of the simulation, adding to the difficulty of effecting movement of the "food" 25 into said mouth opening.

The improved toy preferably embodies a compartment behind the board to receive any play piece or pieces passing through the mouth opening or other opening which 30 may be provided through the board, and a still further object is to provide a guarded opening through which the play piece or pieces may readily be returned from the compartment to the space between the board 35 and the transparent plate, movement of the guard to inoperative position and return of the play piece or pieces being effected by gravity when the toy is turned to the proper position.

40 With the foregoing and minor objects in view, the invention resides in the novel subject matter hereinafter described and claimed, the description being supplemented by the accompanying drawings.

45 Fig. 1 is a front elevation of a toy constructed in accordance with my invention.

Fig. 2 is a vertical sectional view on line 2-2 of Fig. 1.

50 Fig. 3 is a detail vertical section on line 3-3 of Fig. 1.

Figs. 4 and 5 are front elevations showing toys of different designs and slightly different construction.

In the drawings above briefly described, 55 certain specific details of construction have been shown, and while these details will be

hereinafter rather specifically described, it is to be understood at the outset, that within the scope of the invention as claimed, numerous variations may be made.

In Figs. 1, 2 and 3, the numeral 5 designates an appropriate frame structure which may be of any desired configuration and constructed from any adequate number of parts, although said frame construction is 60 preferably rectangular and is formed of front and rear frames suitably secured together.

Secured to the frame 5, I have shown a front, transparent plate 6 of glass or celluloid, a back-board 7 of cardboard or other 65 desired material, and an intermediate or partition board 8 which may also be formed of cardboard or other desired material. At 9, a finishing frame of cardboard has been shown around the peripheral edge of the 70 transparent front plate 6, but such details as this may well be left to the choice of the manufacturer.

Upon the front side of the board 8, I provide a simulation 10 of an animate object, 75 and such simulation may be formed by sketching, painting, embossing or in any other desired manner. This simulation embodies a mouth representation 11, and play pieces 12 are provided between the board 8 80 and the transparent plate 6 to be moved to the mouth representation 11, under the influence of static currents produced by rubbing upon the transparent plate 6, with any desired friction-creating member, such as a 85 felt pad 13. This pad may well be attached to the frame 5 by a cord 14.

The play pieces 12 are constituted either by representations or actualities of food, having characteristics which would make it 90 acceptable to the animate object represented by the simulation 10, and it will thus be seen that the faculty of eating may be well simulated by the use of the toy.

The simulation 10 embodies a movable 100 portion 15, simulating a part which the animate object, simulated by the simulation 10, commonly moves when eating, and this member 15 is adapted for movement under the influence of the static currents induced by 105 rubbing upon the front plate 6. Hence, the habit of eating may be even more realistically and amusingly represented or simulated.

The mouth simulation 10 preferably embodies an opening 16 into which the play pieces 12 may pass, and the member 15 is 110

preferably embodied in the form of a movable mouth part which normally covers or guards the opening 16, adding to the difficulty which the player will experience when attempting to "feed" the simulation 10. This simulation, in the particular figures under discussion, is a representation of a monkey, the movable member 15 represents his upper lip and this member is loosely connected with the board 8 by threads 17.

Any of the play pieces passing through the opening 16, are received in the compartment or receptacle 18 formed behind the board 8, by the back-board 7 and surrounding portions of the frame 5, and to permit return of these play pieces to the front side of the board 8, I provide this board with an additional opening 19 which is preferably located near one corner of the frame. A movable closure 20 however at the front side of the board 8, normally closes the opening 19 and may well be pivotally connected with said board 8, by a piece of fabric or the like 21. When using the toy, the closure 20 preferably remains unaffected by the static currents, but when said toy is inverted, the closure 20 will drop open by gravity and the play pieces 12 may then pass through the opening 19, returning to the space between the front plate 6 and the board 8 from the compartment or receptacle 18, it being of course necessary to shake the frame to cause the play pieces to move toward said opening 19.

It is to be understood that I am not restricted to any particular simulation such as 10, nor to a representation of an animal, as simulations of human beings, birds, fish, reptiles, insects, etc., may be employed at will.

In Fig. 4, a simulation 10^a is provided of a human being, and the mouth simulation 11^a embodies an opening such as 16^a normally guarded by a loosely mounted movable portion 15^a similar to the portion 15 above described. 12^a in this view, designates the play pieces, constituted by representations or actualities of food, and 20^a designates a closure for an opening 19^a like the opening 19 above described.

In Fig. 5, a simulation 10^b of a duck is shown, and the mouth simulation 11^b thereof embodies a movable bill member 15^b corresponding to the members 15 and 15^a, previously described. 12^b in this figure denotes the play pieces, constituted by representations or actualities of food.

From the foregoing, taken in connection with the accompanying drawings, it will be seen that I have produced a new and improved toy, with which the faculty or habit of eating may be simulated in a very amusing and entertaining manner.

Excellent results have been obtained from details herein disclosed, but attention is

again invited to the fact that the present disclosure is for illustrative purposes only.

I claim:

1. In a toy of the type in which a play piece is movable between a board and a transparent plate under the influence of static currents induced by friction upon the plate; a simulation of an animate object upon the board, said simulation embodying a representation of a mouth and a second representation of a part which the animate object simulated moves when eating, said second representation being movably connected with the board and being adapted for movement under the influence of the induced static currents while attempt is being made to move the play piece to the mouth representation under such influence.

2. A structure as specified in claim 1; said mouth representation embodying an opening into which the play piece may pass, said second representation being loosely connected to the board adjacent said opening and adding difficulty to passage of the play piece into said opening.

3. In a toy of the type in which a play piece is movable between a board and a transparent plate under the influence of static currents induced by friction upon the plate; a simulation of an animate object upon the board, an opening in the board into which the play piece may move, and a guard member adding difficulty to passage of the play piece into said opening, said guard member being loosely connected to the board adjacent the opening and being movable under the influence of the static currents induced by friction upon the plate.

4. In a toy of the type in which a play piece is movable between a board and a transparent plate under the influence of static currents induced by friction upon the plate; a simulation of an animate object upon the board, an opening in the board through which the play piece may pass, a compartment behind the board to receive the play piece, an additional opening through which the play piece may return by gravity to the front of the board when the toy is moved to a proper position, and a normally closed closure for said additional opening adapted to open by gravity when the toy is moved to said position.

5. A static induction toy comprising a frame, a transparent front plate, a back board and an intermediate or partition board all secured to said frame, a play piece between the front plate and the partition board, the latter having an opening through which the play piece may pass rearwardly and another opening near the frame through which said play piece may again pass forwardly, and a pivoted gravity-opened closure for said other opening.

6. In a toy of the type in which a play-

piece is movable between a board and a transparent plate under the influence of static currents induced by friction upon the plate; a simulation of an animate object upon the board embodying a representation of a mouth movably attached to the animate representation on said board; the play-piece being constituted by simulation or actuality of food and being adapted for movement to

the mouth representation solely under the influence of the induced static currents, said mouth representation being movable under the influence of said static currents while utilizing the latter to effect movement of the play-piece to said mouth representation. 10

In testimony whereof I have hereunto affixed my signature. 15

FRANK G. HANBACK.
